UNITED STATES PATENT OFFICE.

FREDERICK TEMPLE ALCOCK, OF KAMLOOPS, BRITISH COLUMBIA, CANADA.

TOOL-HOLDER.

1,327,934.

Specification of Letters Patent. Patented Jan. 13, 1920.

Application filed June 7, 1919. Serial No. 302,377.

To all whom it may concern:

Be it known that I, FREDERICK TEMPLE ALCOCK, a subject of the King of Great Britain, and a resident of Kamloops, British Columbia, Canada, have invented certain new and useful Improvements in Tool-Holders, of which the following is a specification.

My invention is an improvement in tool holders, and has for its object to provide a holder of the character specified, especially adapted for connecting a pipe reamer to a set of stocks and dies, in such manner that the reamer will come into operation at the end of the cutting of the thread.

In the drawings:

Figure 1 is a front view of the holder in place on Armstrong or like stocks and dies.

Fig. 2 is a front view of the holder detached,

Fig. 3 is a view at right angles to Fig. 2,

Fig. 4 is a top plan view,

Fig. 5 is a perspective view of the reamer with one section of the holding sleeve,

Fig. 6 is a similar view of the sleeve,

Fig. 7 is a view similar to Fig. 1 showing the attachment applied to the Toledo stocks or dies,

Fig. 8 is a perspective view of the bracket,

Fig. 9 is a similar view with the sections separated.

In the embodiment of the invention shown in Figs. 1 to 6 a substantially U-shaped bracket 1 is connected with the die holder 2, the said bracket having at the ends of its arms angular lugs 3 and 4 which are connected to the holder by screws 5. The lug 3 has an opening for the screw, while the lug 4 is recessed as shown at 5^a for receiving the screw, the arrangement being such that when the screws are loosened the bracket may be swung away from the holder.

The body of the bracket has an opening through which passes a sectional socket, consisting of sections 6 and 7. The sections as shown in Figs. 5 and 6 form a sleeve when they are together for embracing the shank 8 of the reamer 9. This reamer which is of usual construction has the usual shaped shank, which is received within the square bore of the sleeve, and it will be noticed referring to Fig. 5 that intermediate its ends the bore is enlarged and shaped to fit the tapering shank of the reamer.

One section of the sleeve has a notch 10 in the edge of one side wall for receiving a

lug 11 in the edge of the side wall of the other section, to prevent longitudinal movement of the sections with respect to each other. The sleeve is also square in cross section externally, and the corners are threaded as shown. The opening through the body of the bracket 1 is large enough to permit the sleeve to move freely, and is shaped to fit the sleeve, and lock nuts 12 are threaded on to the sleeve above and below the body of the bracket to hold the reamer in adjusted position with respect to the threading dies not shown.

The pipe to be threaded indicated at 13 is engaged by the holder in the usual manner, and the reamer is so held that it will come into engagement with the end of the pipe, at the moment when the last threads are being cut, to simultaneously complete the operation of threading and reaming. The adjustment may be made with the first pipe cut and reamed. Just before the last two or three threads are cut the reamer is adjusted into the end of the pipe, so that it will cut the bur in the pipe end while the last threads are being cut.

In the embodiment of the invention shown in Figs. 7, 8, and 9, the bracket is sectional, consisting of sections 14 and 15, which when joined together form a substantially U-shaped bracket. The arm of each section has a shoe or channel shaped member 16 at its free end, and these shoes are adapted to engage over the web 17 which is the body 18 of the holder 19. The meeting ends of the sections 14 and 15 are rabbeted as shown at 19 to engage one within the other, and the said meeting ends of the sections are pointed or diamond shaped as shown.

At the lapping rabbeted ends the sections have registering square openings 20 for receiving the sleeve 6-7 shown in Fig. 6, and the lock nuts 12 are arranged above and below the body of the bracket 14-15. The reamer 9 held in the sleeve is adjusted with respect to the end of the pipe section 21 in the same manner as it is adjusted to the end of the section 13.

I claim:

1. In combination with a holder for stocks and dies, of means connected with the holder for supporting a reamer in position to engage and ream the end of a pipe as the last of the threads are cut by the dies, said means comprising a sleeve shaped internally to fit the shank of the reamer and divided

longitudinally into sections, and means for adjustably connecting the sleeve to the holder, said means comprising a substantially U-shaped bracket having means for connecting the same to the holder, and lock nuts on opposite sides of the bracket.

2. In combination with a holder for stocks and dies, of means connected with the holder

for supporting a reamer in position to engage and ream the end of a pipe as the last 10 of the threads are cut by the dies, said means comprising a sleeve shaped internally to fit the shank of the reamer and divided longitudinally into sections, and means for adjustably connecting the sleeve to the holder.

FREDERICK TEMPLE ALCOCK.
